UNITED STATES PATENT OFFICE.

LOUIS V. HOMAN, OF SOUTH DARTMOUTH, MASSACHUSETTS.

APPARATUS FOR OPERATING GATES, &c.

1,386,112.

Specification of Letters Patent.

Patented Aug. 2, 1921.

Application filed June 1, 1920. Serial No. 385,409.

To all whom it may concern:

Be it known that I, LOUIS V. HOMAN, a citizen of the United States, residing at South Dartmouth, in the county of Bristol 5 and State of Massachusetts, have invented new and useful Improvements in Apparatus for Operating Gates, &c., of which the following is a specification.

This invention relates to a barrier such as 10 a gate, arranged in a vertical plane and mounted to swing horizontally on a vertical axis, the gate being, for example, a barrier across a driveway, and adapted to open and close the latter.

15 The invention has for its object to provide means operable by a vehicle approaching the gate to open it, and by a vehicle leaving the opened gate to close it.

The invention is embodied in the improvements which I will now proceed to describe 20 and claim.

Of the accompanying drawings forming a part of this specification,—

Figure 1 is a plan view illustrating the 25 invention conventionally or diagrammatically.

Fig. 2 is a front elevation, showing the gate closed.

Fig. 3 is a section on line 3—3 of Fig. 2, 30 and a plan view of parts below said line.

Fig. 4 is a sectional view of one of the vehicle-operated platforms and parts associated therewith.

Fig. 5 is a section on line 5—5 of Fig. 2.

35 Fig. 6 is a detail view showing the relation of the controlling arm to the motor, and to the oscillatory arm.

The same reference characters indicate the same parts in all of the figures.

40 In the drawings, 12 represents a vertical post, adapted to be rotated in fixed bearings, the bearings for the lower end of the post being below a surface 13, which may be the surface of a driveway. The bearings 14 for 45 the upper end of the post may be attached to a fixed post or standard 15.

To the post 12 is attached a barrier, such as a gate 16, which may be of any suitable construction, and is adapted to swing over 50 the surface 13 to open and close the latter. I provide rotating means adapted to rotate

the post in one direction to open a gate, and in the opposite direction to close the same, said means being preferably embodied as next described.

55 17 represents the casing, and 18 the shaft of a reversible motor, which may be of any suitable character, the motor being preferably a reversing field electric motor of well known construction, and having a controlling member which is the arm 20 of a reversing switch, said arm projecting through the slot 19 in the casing. The motor may be fixed within a housing 21 at one side of the driveway.

60 The motor constitutes an element of a two-way post-rotating means, whereby the gate may be opened and closed, the motor being rotated in a direction to open the gate when the arm 20 is moved from one end of 65 the slot 19, and rotated in the direction required to close the gate when the arm 20 is moved to the opposite end of said slot. When the arm 20 is in the neutral position, or central between the ends of the slot 19, 70 the motor is stopped.

75 The gate post 12 is provided at its lower end portion with a worm gear segment 22, which meshes with a worm 23, fixed to a horizontal rock-shaft 24, said shaft being 80 journaled in suitable bearings below the surface 13. Torque-transmitting connections are provided between the motor-shaft 18 and the rock-shaft 24, said connections as here shown, including a sprocket-wheel 25, 85 fixed in the motor-shaft, a sprocket-wheel 26 journaled in fixed bearings below the motor, a sprocket-wheel 27 fixed to the rock-shaft 24, and a sprocket-chain 28 connected with the wheels 25 and 26, and a sprocket-chain 29 connecting the wheel 27 with a smaller sprocket-wheel 30, which is fixed to and coaxial with the wheels 26.

90 Located in the driveway at suitable points, are two platforms 31 and 32, which are normally raised, and adapted to be depressed by a vehicle-wheel bearing thereon. Each platform and the power-transmitting means connected therewith, may be constructed as shown by Fig. 4, which may be understood 95 to represent the platform 31. 35 represents an oscillatory arm pivoted at 36, and pro-

vided at its swinging end with a slot 37, which receives a portion of the controlling member 20. Connected with the swinging end of the arm 35 are two oppositely extending cables 38 and 39. The cable 38 extends to a point under the platform 31, and is there connected with one arm of a lever 40, fulcrumed at 41. The opposite end of said lever is connected with the platform 31 by a link tie-rod 42, pivoted at 43 to the platform, and provided with a fixed spring abutment 44, and with a removable spring abutment 45 bearing on the lever 40, a spring 46 being interposed between the abutments 44 and 45. Yielding connections are thus provided between the platform 31 and the lever 40. The cable 39 is connected in like manner with the platform 32.

The platform 31 is located at one side of the opening covered by the gate, and the platform 32 is located at the opposite side of said opening, the arrangement being such that when a wheel 47 of a vehicle such as a motor car, is approaching the gate, it depresses the platform 31 and moves the oscillatory arm 35 to position to cause the motor to open the gate. When the vehicle has passed through the gate, and the wheel 47 bears on the platform 32, the motor is reversed and caused to close the gate.

After each opening and closing of the gate the motor is automatically stopped by means including two tappets 48 and 49, fixed to the post 12, a horizontal lever 50 fulcrumed at 51 and having one of its ends in the path of the tappets 48 and 49, and a rod 52 connecting the other arm of the lever 50 with the oscillatory arm 35. The arrangement is such that when the gate reaches one extreme of its movement, the tappet 48 causes the oscillatory arm 35 and controlling member 20 to assume the neutral position shown by Fig. 5, and when the gate reaches the other extreme of its movement, the tappet arm 49 performs the same function.

The cables 38 and 39 may be made in sections, adjustably connected by turn-buckles 53, as shown by Fig. 5. Said cables are guided by suitable means, including shives or pulleys 54, and tubular conduits 55 located below the surface 13.

The gate may be composed of two leaves or sections 16 and 16^a, as indicated by Figs. 1 and 2, in which case the rock-shaft 24 is elongated and provided with a worm 23^a, meshing with a worm-gear sector 22^a on the post 12 of the gate section 16^a, the direction of the threads of the worm 23^a being opposite to that of the worm 23, so that the two gate sections are swung simultaneously in opposite directions.

When a two-leaved gate is employed, the vehicle-operating means for opening and closing the gates will include another plat-

form 31^a having the same function as the platform 31, and another platform 32^a having the same function as the platform 32.

I claim:

1. Gate-operating mechanism comprising, in combination, a reversible motor, a motor-driven gate, torque-transmitting connections between the motor and the gate, and motor-controlling mechanism operable by a vehicle approaching the gate to open the gate, and by a vehicle leaving the gate to close the gate, said mechanism including normally raised platforms located at opposite sides of the gate and depressible by vehicle wheels approaching and leaving the gate, a controlling member associated with the motor and adapted to occupy either of two operative positions and an intermediate neutral position, an oscillatory arm engaged with said controlling member, and adapted to move the latter to either of said positions, flexible connections between said platforms and said arm, and means operable by the gate when the latter reaches an open and a closed position, to move the oscillatory arm and controlling member to the neutral position of the latter, and thus stop the motor.

2. Gate-operating mechanism comprising, in combination, a reversible motor, a motor-driven gate, torque-transmitting connections between the motor and the gate, and motor-controlling mechanism operable by a vehicle approaching the gate to open the gate, and by a vehicle leaving the gate to close the gate, said mechanism including normally raised platforms located at opposite sides of the gate and depressible by vehicle wheels approaching and leaving the gate, a controlling member associated with the motor and adapted to occupy either of two operative positions and an intermediate neutral position, an oscillatory arm engaged with said controlling member, and adapted to move the latter to either of said positions, flexible connections between said platforms and said arm, oppositely acting tappet arms, movable in opposite directions by the gate, and connections between said arms and the controlling member to move the latter to its neutral position and stop the motor when the gate reaches an open and a closed position.

3. Gate-operating mechanism comprising, in combination, a reversible motor, a motor-driven gate, torque-transmitting connections between the motor and the gate, and motor-controlling mechanism operable by a vehicle approaching the gate to open the gate, and by a vehicle leaving the gate to close the gate, said mechanism including normally raised platforms located at opposite sides of the gate and depressible by vehicle wheels approaching and leaving the gate, a controlling member associated with

the motor and adapted to occupy either of two operative positions and an intermediate neutral position, an oscillatory arm engaged with said controlling member, and adapted to move the latter to either of said positions, 5 flexible connections between said platforms and said arm, oppositely acting tappet arms movable in opposite directions by the gate, a pivoted lever in the path of said arms, and a rod connecting said lever with said oscillatory arm.

In testimony whereof I have affixed my signature.

LOUIS V. HOMAN.
